UNITED STATES PATENT OFFICE

ISIDORO BIGNAMI, ERCOLE GALASSINI, EMILIO FRANCHI, AND GIULIO PONS, OF BRESCIA, ITALY, ASSIGNEES TO SOCIETA ALTI FORNI, FONDERIE, ACCIAIERIE E FERRIERE FRANCHI-GREGORINI, OF BRESCIA, ITALY

CENTRIFUGAL TUBE-CASTING APPARATUS

Application filed May 20, 1929. Serial No. 364,616.

Machines for casting tubes in which the metal in molten state is fed to and poured by means of a pouring channel into a rotating mould are already known, the pouring channel and the mould having a relative movement.

Nevertheless, when tubes of small diameter are to be cast, this arrangement is open to considerable objections because the pouring channel tends to oscillate by reason of the shocks to which it is inevitably subjected, and consequently it may strike against the sides of the rotating mould and thereby interfere with the regularity of the castings.

15 The present invention has for its object a machine wherein the pouring channel is fixed while the mould is mounted to rotate upon a carriage which is movable longitudinally, the two movements, that is, translation of the 20 carriage and rotation of the mould, being controlled through suitable transmissions by two electric motors, the one which controls the rotation being mounted upon a carriage and movable therewith.

25 The other motor controls the straight motion of the truck carrying the mould, and also controls the tilting of the reservoir containing the molten metal, by which means the advantage is obtained over other similar arrangements having these two motions controlled by distinct motors that a uniform thickness of the cast tubes is secured.

The single figure of the accompanying drawing shows by way of example and in 35 diagrammatic longitudinal section the principal features of the improved machine.

In the arrangement illustrated, 1 indicates a carriage mounted on wheels 8 running on guides 9 and provided with rollers 2 mounted upon a longitudinal shaft 2' driven by means of a suitable transmission 7 from an electric motor 5 mounted upon a suitable base 6 fixed to a metal casing 10 hereinafter mentioned.

45 Upon the rollers 2 rest the collars 3' of the tubular rotating mould 3 into which the fixed pouring channel 3'' pours the molten metal which comes from a feed reservoir B of any suitable type.

50 The rotation of rollers 2 causes the rotation

of the mould 3. The motor 5 may, with the aid of a suitable transmission, control a carriage-feeding mechanism which imparts to the carriage an axial translation movement at a suitable speed; this movement may also be given to the carriage by another independent motor by means of controls of any other kind. In the construction shown, this movement is effected by a motor 11 which also controls the reservoir B.

The mould is enclosed in the cylindrical casing 10 which is made of sheet iron and is adapted to prevent the dispersion of the cooling water which is sprayed by means of perforated tubes upon the outer surface of the 65 rotating mould.

The accessory arrangements may of course be varied without departing from the spirit of the invention.

What we claim is:

1. A centrifugal tube-casting apparatus, comprising a hollow, cylindrical casing; a longitudinally-moving carriage whereon the casing is mounted; a tubular mould mounted within said casing to move longitudinally therewith; means for rotating said mould relatively to the casing; a stationary pouring channel extending within said mould; a tiltable feeding reservoir to receive molten metal and discharge it into said channel; an electric motor; a driving connection between said motor and reservoir for tilting the latter; and a separate driving connection between the motor and carriage to effect the advance of said carriage.

2. A centrifugal tube-casing apparatus, comprising a hollow, cylindrical casing; a longitudinally-movable carriage whereon the casing is mounted; a tubular mould mounted within said casing to move longitudinally therewith; a motor mounted on the upper portion of said casing; a connection between said motor and said mould to rotate the mould relatively to the casing; a stationary pouring channel extending within the mould; a tiltable feeding reservoir to receive molten metal and discharge it into said channel; a motor external to said casing; a driving connection between the last-named motor and the reservoir for tilting the latter; and a sepa-

rate driving connection between said last-named motor and the carriage to effect the advance of said carriage.

5 3. In a centrifugal tube-casting apparatus, a longitudinally-movable carriage; a tubular mould supported to move therewith; a stationary pouring channel extending within said mould; means for rotating said mould about and relatively to said channel; a tiltable feeding reservoir to receive molten metal and discharge it into said channel; a motor; a driving connection between said motor and reservoir for tilting the latter; and a separate driving connection between the motor and carriage to effect the advance of said carriage.

10 In testimony whereof we affix our signatures.
